HIGHWAY GUARD

Michael J. Gill, Secaucus, N. J.

Application July 18, 1939, Serial No. 285,157

4 Claims. (Cl. 256—13.1)

The invention relates to highway guards and more particularly to protective means for the sides of highways.

The primary object of the invention is the provision of a guard of this character wherein dangerous sidings to a roadway will be rendered safe, avoiding motor or other traffic from leaving the roadway, possibly resulting in the loss of life, or injury to the person and damage to property and at the same time minimizing the possibility of disruption of the guard due to impact of the vehicle therewith when the latter swerves from a straight course along the roadway.

Another object of the invention is the provision of a guard of this character wherein it possesses yieldability, shock absorption and is devoid of protruding portions so that a vehicle will not become entangled therewith or damaged thereby when making contact and resultant in safety guarding life and property.

A further object of the invention is the provision of a guard of this character wherein road accidents will be reduced to a minimum and safe traffic over a highway assured.

25 A further object of the invention is the provision of a guard of this character which is simple in its construction, thoroughly reliable and efficient in operation, economic for erection, strong, durable, and inexpensive to manufacture and 30 install.

With these and other objects in view, the invention consists in the features of construction, combination and arrangement of parts as will be hereinafter more fully described in detail, illustrated in the accompanying drawings, which disclose the preferred embodiment of the invention and pointed out in the claims hereunto appended.

In the accompanying drawings:

40 Figure 1 is a fragmentary perspective view of a highway guard constructed in accordance with the invention being partly broken away.

Figure 2 is a vertical transverse sectional view thereof.

45 Figure 3 is a horizontal sectional view through one of the guard posts.

Figure 4 is a horizontal sectional view through an overlapped joint of the guard.

50 Figure 5 is a fragmentary sectional view taken on the line 5—5 of Figure 2.

Similar reference characters indicate corresponding parts throughout the several views in the drawings.

55 Referring to the drawings in detail, A designates generally a portion of a roadway being

constructed from cementitious or concrete material while extending laterally with respect to the roadway at a selected side thereof are spaced extensions 10 made from the same material as the roadway and are imbedded in soft shoulders 5 11 of conventional form. These extensions 10 may be integral with the body of the roadway or separate therefrom.

Rising vertically from the outermost ends of the extensions 10 are posts 12, these being made 10 from the same material as the said extensions and body of the roadway and have imbedded therein the shanks of eye bolts 13, the shanks being provided with nuts 14 for the fastening of the eye members within the posts 12 with the 15 eyes thereof projecting from the side faces of these posts toward the roadway A and trained through the eyes of these eye members 13 are steel wire cables 15, these being extended in spaced parallel relation to each other longitudinally of the roadway and are held in a taut condition in any desirable manner for functioning as guard cables.

Partially imbedded in the extensions 10 and posts 12 are racks each formed from a single 25 length of stiff but inherently resilient wire bent into a substantially L-frame 16, being upright and carried a distance above the uppermost portion of the companion post 12 where the said frame has provided therein a coil 17 for an arm 30 18 which at its free end is provided with a hook 19 engageable with a coil 20 formed from a horizontal limb 21 of this frame 16. This limb 21 is imbedded not only in the extension 10 but also in the roadway body A, the coil 20 being also 35 imbedded in the said extension 10. The coils 17 and 20 allow a determined yieldability to the arm 18 resultant from impact from a vehicle when striking the guard before and hereinafter described.

40 Carried upon the arms 18 of the frames 16 are guard or shield plates 22, these being overlapped at ends adjacent each other and passed through the overlaps 23 are clamping hooks 24 which engage the arms 18 and in this manner the plates 45 22 are joined with the arms 18 of the frames 16. The plates 22 in their overlapped relationship have longitudinally outstruck therefrom in the direction of the roadway a protruding rib 25 being disposed closer to the bottom edges than to the 50 top edges of the said plates and this rib strengthens or reinforces these plates to withstand impacts with vehicular traffic when a vehicle leaves the roadway or swerves into the highway guard. The arms 18 through the coils 17 and 20 cushion 55

the plates 22 and function as shock absorbers built into the guard.

The plates 25 are disposed spaced from the cables 15 and the angular disposition of the arms 5 18 to the vertical hold these plates 22 in a lateral sloping arrangement. A vehicle lost of control strikes the plates 22 which through the build of the guard absorbs the impact of the vehicle and avoids the possibility of such vehicle running off 10 of the roadway A and in this manner saving life and eliminating damage to property.

What is claimed is:

1. A highway guard comprising posts arranged perpendicular at a side of a roadway, extensions 15 from said roadway and supporting said posts, substantially L-shaped frames partially imbedded vertically in the posts and said extensions and having upper and lower coils, arms formed with said frames and a part of one coil and hooked 20 with the other coil of each frame, and shield plates supported by said arms.

2. A highway guard comprising posts arranged perpendicular at a side of a roadway, extensions 25 from said roadway and supporting said posts, substantially L-shaped frames partially imbedded vertically in the posts and said extensions and having upper and lower coils, arms formed with said frames and a part of one coil and hooked with the other coil of each frame, shield plates

supported by said arms, and guard cables fastened to said posts rearwardly of the shield plates.

3. A highway guard comprising posts arranged perpendicular at a side of a roadway, extensions from said roadway and supporting said posts, substantially L-shaped frames partially imbedded vertically in the posts and said extensions and having upper and lower coils, arms formed with said frames and a part of one coil and hooked with the other coil of each frame, shield plates 10 supported by said arms, guard cables fastened to said posts rearwardly of the shield plates, and clamping hooks connecting the said plates to the arms.

4. A highway guard comprising posts arranged 15 perpendicular at a side of a roadway, extensions from said roadway and supporting said posts, substantially L-shaped frames partially imbedded vertically in the posts and said extensions and having upper and lower coils, arms formed with 20 said frames and a part of one coil and hooked with the other coil of each frame, shield plates supported by said arms, guard cables fastened to said posts rearwardly of the shield plates, and clamping hooks connecting the said plates to the 25 arms, the plates having ends adjacent each other disposed overlapping one another.

MICHAEL J. GILL.
